UNITED STATES PATENT OFFICE.

WILLIAM MARRETT, OF TOLEDO, OHIO, ASSIGNOR TO THE LIBBEY GLASS COMPANY, OF SAME PLACE.

DESIGN FOR A GLASS DISH.

SPECIFICATION forming part of Design No. 27,116, dated May 25, 1897.

Application filed April 1, 1897. Serial No. 630,310. Term of patent 7 years.

To all whom it may concern:

Be it known that I, WILLIAM MARRETT, of Toledo, county of Lucas, and State of Ohio, have invented a certain new and original Design for a Glass Dish; and I do hereby declare that the following is a full, clear, and exact description of the invention, which will enable others skilled in the art to which it appertains to make and use the same, reference being had to the accompanying drawings, and to the letters of reference marked thereon, which form part of this specification.

This design relates to a glass dish and pertains particularly to the ornamentation of the external surface thereof.

The drawings represent, in Figure 1, a bottom plan view of a dish containing the design; and in Fig. 2 a transverse section on lines $x x$, Fig. 1.

The leading features of my design are a central prismatic stud surrounded with radial triangular lines, with five oblong fields extending from midway the circular area of the dish, one end of each oblong field embellished with an oblong area of diamond-shaped cross-hatching, with the opposite end embellished with prismatic rays and a concentric row of fields with arched conical lines apexed toward the edge of the dish, and inverted curved lines in inverse order, having central studs centrally of the fields, and a marginal row of like-shaped fields concentric thereto, having diamond-shaped checkers with checkered triangular fields arranged upon the extreme outer diameter, having a plurality of minute prisms.

1 designates the central prismatic stud surrounded with radial triangular lines 2, the stud and field being central of a plurality of lines described by the formation of five oblong fields 3, which extend from side to side midway the circular area of the dish, one end 4 of each oblong field 3 being embellished with an oblong area 5 of diamond-shaped cross-hatching. The opposite ends 6 are embellished with prismatic rays 7. Intermediate the ends of the oblong fields is a concentric row 8 of fields of arched conical lines 9, apexed toward the edge of the dish, and inverted curved lines 10 in inverse order, having central studs 11 centrally of the fields, there being a marginal row 12 of like-shaped fields concentric thereto, having diamond-shaped checkers with checkered triangular fields 13, arranged upon the extreme outer diameter, having a plurality of minute prisms.

The effect of the alternate rays and checkers, together with the concentric row of prismatic studs, is a very pleasing one.

What I claim is—

The design for a glass dish substantially as shown and described.

In testimony that I claim the foregoing as my own I hereby affix my signature in presence of two witnesses.

WILLIAM MARRETT.
